HOT LINE CONNECTOR

Albert J. Moore, Union, N. J. assignor to The Thomas & Betts Co., Elizabeth, N. J., a corporation of New Jersey

Application February 1, 1947, Serial No. 725,775

2 Claims. (Cl. 173—273)

1

The invention relates in general to electric connectors and specifically relates to connectors known as hot line or live line connectors or clamps.

It has been known in this art to provide such connectors with tap-lines variously secured thereto so as to trail therefrom with two-jaw clamping means fashioned for hooking over an overhead hot live or main line, and then, by means of a long reach rod usually called a hot clamp stick to turn the screw of a clamping mechanism reacting between the jaws to secure the connector both mechanically and electrically to the main line.

These known devices do not give satisfaction under all of the conditions under which they must operate in actual practice. One difficulty which has developed with such devices now on the market is that the clamping screws which bear on the jaws eventually back off from their initial tightly secured position under the influence of vibration and bodily swing movement present in the main line. Also expansions and contractions to which such known devices are subjected, by reason of the wide range of temperatures to which these devices are exposed, contribute to the dissatisfaction with known types of such connectors.

The primary object of this invention is to provide a simple form of hot line connector which will avoid such objections to presently known devices, and to provide a connector of the clamping type which will be easy to apply to the overhead live line, which can be held thereto resiliently at least during the initial clamping operations, and which when once securely clamped thereto with a non-resilient engagement will so remain in locked position until intentionally unlocked in the act of removing the same.

Broadly this aspect of the invention is attained by providing a single, screw-controlled combined clamping and locking mechanism for squeezing the jaws on to the main line and characterized by having two operative positions, in one of which positions the jaws are spring backed resiliently and thus free to open automatically to receive the main line and subsequently resiliently clamped between the jaws by the spring; and in the other position of the clamping mechanism the jaws are positively screw locked in their line squeezing positions and thus not free to open accidentally under service conditions.

The present disclosure features in such form of clamping mechanism a single screw control fashioned to be operated at a distance by means of a long reach or hot clamp stick which control can be rotated to change the clamping pressure

2

on the jaws from a spring imposed pressure to an inflexible rigid chain of pressure transmitting parts leading through the screw from one to the other of the jaws and thus to cause a locking of the jaws in their clamping position.

Screw type clamps now in general use are cast or forged and are rather heavy masses of metal. Under certain wind conditions the weight of these clamps develop a fly wheel effect by reason of its vibration with resulting damage to the line. As it is an object of the present disclosure to provide a long contact between connector and line to obtain better distribution of contact pressure and permit essential stream line flow of current, it would follow that known forms of screw type clamps would become even heavier if developed to include these desirable features.

Accordingly it is another object of the invention to provide a long contact and at the same time to reduce the mass of metal in the connector so as to minimize the undesirable fly wheel effect.

It is also known altho' not a general practice to make such jaw clamps of sheet copper, usually from blanks stamped from sheet material and bent to shape and usually bent into a somewhat U-form. Of course, it is an economical requirement that such clamps be made cheaply and thus of the least amount of material particularly in its thickness dimension.

With known forms of such clamps undesirable stresses and strains were developed in the material especially in the region adjacent the fulcrum of the jaws and in the areas thereof which contain the screw clamping mechanism. These strains were developed both in the course of bending the blanks into their U-form as well as subsequently during the installing of the device on the main line and also still later while the clamps were in operation especially when in use over long periods of use, and the resulting weakening of the structure by reason of such strains became quite noticeable in the cases where a too thin gauge of stock material was used.

Accordingly another object of the invention and featuring economy in production cost is to provide a connector which can be made of a less gauge material than has been found possible heretofore and which will be free, or at least substantially free, of any such distorting strains and stresses even when made of an unusually thin gauge of material like springy sheet copper.

This object is attained first by making the clamp of two separable parts, each part having its sheet metal corrugated and thus reinforced in those regions where bending stresses were most

liable to develop; and second, by providing a form of knuckle-like, initially loose form of hinge connection between the parts so separately formed and which hinge connection will be capable of automatically adjusting its elements to fit the main line without causing strain in one part to be transmitted across the fulcrum or hinge to the other part.

Various other objects and advantages of the invention will be in part obvious from an inspection of the accompanying drawings and in part will be more fully set forth in the following particular description of one form of hot line connectors embodying the invention, and the invention also consists in certain new and novel features of construction and combination of parts hereinafter set forth and claimed.

In the accompanying drawings:

Fig. 1 is a plan view looking down upon a preferred embodiment of the invention installed in operative position hung from a main hot line;

Fig. 2 is a view in side elevation of the device shown in Fig. 1 in position as it is being applied to the main line, with the bolt element of the clamping mechanism in its lowermost retracted position, and with the jaws distended into open position by the intruding main line;

Fig. 3 is a vertical sectional view taken on the line 3-3 of Fig. 1, with a showing similar to that of Fig. 2, but with the bolt advanced to lock the jaws in position clamped to and hung from the main line;

Fig. 4 is a plan view of the underside of the lower jaw shown in the preceding figures and,

Fig. 5 is a detail view in axial section taken on the line 5-5 of Fig. 3 except that the bolt is in its retraced position and the bearing sleeve lowered in Fig. 2.

In the drawings there is shown a hot line connector 10 used for connecting the conductor A of an overhead main line B with the conductor C of a tap line D secured to and trailing down from the connector 10.

The connector includes a clamp 11 formed of two separable jaw forming elements, an upper element 12 and a lower element 13, each formed from a blank of sheet copper of a gauge of material sufficiently thin to have at least a slight degree of resiliency particularly in the clamp forming areas not intentionally reinforced as hereinafter described. In the illustrated case the elements are stamped from No. 14 (064) sheet copper.

The two elements are hingedly connected adjacent one end and the portions thereof adjacent to the hinge are normally in substantially parallel relation to form an upper jaw 14 and a lower jaw 15. The outer free end portion of the upper element beyond the jaw 14 forms an outstanding reach plate or hook 16 and the outer free end of the lower element 13 is bent down sharply from the lower jaw 15 to form a depending plate 17 to which the tap line D is secured and from which it hangs vertically. The reach plate 16 and the rounded portion of the lower element between the plate 17 and the jaw 15 form a wedge-like outwardly open throat for guiding the main line A onto the seat provided therefor at the outer portions of the jaws 14 and 15.

The jaws are at all times under a squeezing load imposed thereon by a combined clamping and locking mechanism 18 herein featured for clamping the jaws onto the conductor A both during the installing of the connector on the main line as well as later after the connector is

in its fixed operative engagement with the main line.

The upper element 12 is a flat strip of metal straight for the major portion of its length; is of maximum width as indicated in Fig. 1 along the portion thereof designed to engage the main line conductor A, and reduces in width therefrom in both directions to economize in the use of metal where not needed. One end of the strip which forms the upper element 12 is rounded back upon itself to form a wide closed lifting or removing eye 19 at one end of the device and located so as to be conveniently accessible for engagement by a reach rod.

The flat portion of the strip forming the upper jaw 14 meets the adjacent side of the eye approximately at right angles thereto to form an open downwardly facing semi-cylindrical groove 20. Immediately in advance of the groove the strip is provided with two punchings projecting downwardly from the body of the strip to form a pair of downwardly projecting embossments 21-22 disposed in transverse alignment and parallel to the groove. The groove 20 on one side and the embossments 21-22 on the other side of a transverse line coat to form the socket element of a readily separable hinge connection 23 forming the fulcrum or hinge line of the jaws. Just in advance of the embossments 21-22 the strip is punched completely therethrough to provide a nut receiving hole 24. In this hole is fastened the inner end of a long upstanding nut 25 forming part of the clamping mechanism 18. The lower end of the nut is peened or rolled over the edge of the hole and the nut is thus securely and rigidly fastened to the top jaw and projects upwardly therefrom as a rugged column. The lower portion of the bore of the nut is provided with threads 26 preferably of small pitch and above the threaded portion a bore is enlarged to provide a grease chamber 27. The outer end of the chamber is normally closed by a readily removable disc 28.

The jaw 14 is reinforced in the area of the nut by a system of corrugations including a ring 29 in which the hole 24 is centered and from opposite sides of which ring extend two parallel legs 30-31 projecting forwardly for substantially the full length of the upper jaw 14 as shown in Fig. 1. Another of the corrugations 32 extends transversely of the jaw from edge to edge, intersects the corrugations 30 and 31 and forms on its underside a downwardly facing channel or groove for fitting over the conductor A as shown in Fig. 3. The outer ends of this channel are flared outwardly and upwardly to provide half bell-shaped or funnel-like ends 33 and 34 of greater cross section at their outer ends than the portions of the conductor contained therein. Adjacent the inner side of the groove 32 the metal is lanced out and bent inwardly from the plane of the strip to provide a pair of depending lugs 35-36 acting as stops for limiting the advance of the conductor A as it is moved into position located between the jaws 14 and 15 as shown in Fig. 2.

The lower element 13 as best shown in Fig. 14 is formed from a blank of less length than the blank from which the upper element was formed and is bent midlength into an L-form to form the lower jaw 15 and the vertically depending plate 17. One end portion of the jaw is bent back sharply on itself to form a knuckle-like ridge 37 fitting in the groove 20 and constituting the companion element of the hinge connection 23. The jaw 15 is corrugated to provide reinforcements

identical with and facing those described for the upper jaw and includes a ring 38, in this case forming a rugged bearing ring, and also includes on its inner side an upwardly facing channel or groove 39 facing the groove 32 and coating therewith to form a seat for the conductor A.

The bearing ring 38 is provided centrally thereof with a bolt hole 40 in alignment with the open threaded end of the bore of the nut. The jaw 13 is provided with a pair of rectangular holes 41-42 for receiving the stop lugs 35-36 when the jaws without the conductor A therebetween are closed in bearing engagement with each other.

The clamping mechanism 18 includes a long eye-bolt 43 having at its lower end a turning eye 44. The other or upper end of the bolt is provided with threads 45 in threaded engagement with the threads 26 of the nut 25. The lower unthreaded shank portion of the bolt is passed freely through the bolt hole 40 as best shown in Fig. 3. At its intruded end the bolt is provided with a stop flange 54 operating in the grease chamber 27. The retreat of the bolt is limited by the engagement of the flange 54 with a shoulder defining the bottom of the grease chamber.

The smooth shank of the bolt is provided below the jaw 13, as best shown in Fig. 5, with an integral bearing flange 46. A sleeve 47 is mounted on the shank free to rotate thereon and is provided at its upper end with an inturned flange 48 riding on the flange 46 and provided at its lower end with an out-turned flange 49 forming a spring seat. A coiled spring 50 at all times under load encircles the sleeve 47 and bears at one end on the flange 49 and at the other end bears against the underside of the embossed ring 38. It is a feature of this disclosure that the length of the sleeve is slightly greater than the length of the solid column which would be formed if the spring was compressed with its turns in contact to form such solid column. It is within the scope of this disclosure to have the flanges 48-49 as fixed stops formed integrally with or otherwise secured to the shank of the bolt in those cases where the rotating sleeve 47 was not desired or needed.

The depending plate 17 is progressively reduced in width towards its lower most portion and is thus somewhat triangular in shape when viewed in front elevation. At its lowermost point the plate terminates in a long straight integral extension which is rolled back longitudinally upon itself to form a long open-like tubular socket 51 designed to receive and be secured to an exposed end of the conductor C of the tap line D.

It is suggested that the relatively flat portion of the depending plate 17 in the part thereof between the bend at its upper portion and the socket 51 indicated by the reference character 56 and in prolongation of the socket be reinforced by corrugating it. It is also suggested that the part so corrugated be provided with a hole 55 extending therethrough to provide means for attaching another wire (not shown) corresponding to the lead C or to receive an auxiliary connection.

Normally, that is, before the conductor A is installed in place, the jaws 14-15 are in mutual bearing engagement under load imposed thereon by the tensioned spring 50 with the lugs 35-36 intruded into their respective holes 41-42, and with the elements of the hinge connection held resiliently in interbearing engagement by reason of the load imposed thereon by the spring.

In preparing the connector for use an end of the tap conductor C is inserted into the bore of

the socket 51 and the socket crimped thereon at one or more places as indicated by the crimps 52-53 formed by means of a crimping tool or machine following conventionally practices in securing conductors to tubular members.

In operation and assuming that the tap line has been secured to the connector as previously indicated, the assembly is lifted by a suitable lift rod G engaging in the lift eye 19 or bolt eye 44 until the reach plate 16 overhangs, finds and is hooked over the exposed portion of the conductor A. The broad surface presented by the underside of the plate 16 resting on the main line tends to bring the seat formed by the grooves 32-39 into alignment with the conductor. By means of the lift stick the connector is moved laterally relative to the conductor A and in the direction indicated by the right arrow on Fig. 2, that is, from right to left of this showing. The conductor A in effect slides on the underside of the plate 16 and moves towards the crotch of the then closed jaws to force them apart transversely and against the resistance of the spring 50; at this time the spring is under its least load. Eventually the conductor A reaches the position indicated in Fig. 2 having forced the jaws apart causing them to swing about the hinge line provided by the hinge connection 23. As the two elements 12-13 are not integrally connected at the hinge, as is usually with such devices, the jaws are free to adjust themselves automatically each to fit its associated groove to the main line A without restraint from the other clamping jaw similarly. This may mean that the ledge 37 is not exactly parallel to the groove 20 in which it turns but any deviation which under any condition is small will be immaterial to the hinge action.

As the conductor A reaches the position shown in Fig. 2 and starts on to its channel seat, the spring acts with a snap action to force the conductor squarely into the seat as shown in Fig. 3. The stops 35 and 36 are disposed in the path of seating movement of the conductor and prevents the conductor from overshooting its seat. Up to this point the jaws are solely under control of the spring. The spring loaded tension is sufficient where only a temporary and quick connection is desired for any reason, so that the device may be used with the bolt in retracted position and without necessarily using the locking mechanism herein featured.

When the conductor is so seated the lower exposed eye end of the bolt is engaged by a suitable form of reach rod H and rotated clockwise thereby, as indicated by the elliptical arrow in Fig. 2. The bolt is advanced in the nut until the upper flanged end 48 of the sleeve 47 engages and bears firmly on the underside of the ring 38 as indicated in Fig. 3, incidentally further compressing the spring 50. The clearance between the limiting stops 28-54 at the top of the bolt is prefixed so that the desired degree of positive locking pressure is imposed between the clamping jaws in their engagement with the main line held between them. During the rotation of the bolt before its solid engagement with the lower jaw is had the spring is acting to hold the connector resiliently to the main line and thus acts to stabilize the device against axial rotation around the axis of rotation of the bolt. When the bolt is fully advanced the conductor A is held rigidly between the clutch jaws 14-15, primarily by reason of the solid metal-to-metal engagement of the sleeve 47 with the lower jaw 15. Differently expressed,

there is a solid inflexible chain of connected parts

leading from the rugged nut 25, through the chain of metal parts formed by the bolt, its flange 46, the sleeve 47, and its flange 48 bearing on the ring 38 of the lower jaw. It is appreciated that at this time the spring 50 under its maximum load is bearing on the flange 46 in a tendency to provide sufficient friction to resist any tendency of the bolt to back out of the nut by reason of line vibration or otherwise.

When it is desired to disconnect the tap from the main line it is simply necessary to rotate the bolt counter-clockwise as indicated by the elliptical arrow in Fig. 3 so as to remove the collar 47 as a whole from its bearing engagement against the lower jaw, and in this way the jaws are restored to the control of their single and sole squeeze force inherent in the spring. When the bolt has been retracted to the limit permitted by stop flange 54 or sufficiently to permit the jaws to be sprung apart, and thus permit the conductor to clear its seat, an outward pull on the lift eye, that is, from left to right of the showing in Fig. 3, permits the spring to react between the conductor A and the jaws to kick the connector as a whole backward and away from the conductor with a snap action and thus the device operates both when being applied to and when removed from the hot line to act in a tendency to prevent damage to the conductor A due to arcing. Other applications containing subject matter similar to the disclosure herein are applicant's pending application, Serial No. 36,669, filed July 2, 1948, and an application filed by Lucian A. Thomas, Serial No. 633,748, filed December 8, 1945, now Patent No. 2,555,099, issued May 29, 1951.

I claim:

1. A hot line tapping device including two sheet metal jaws forming elements hingedly connected at one end, each element being corrugated adjacent its mid-length to provide a pair of inwardly facing grooves for receiving the line therebetween, one of the elements provided between its groove and its hinged end with a nut fixedly secured thereto, the other element in the part thereof facing the nut provided on its outer side with a bearing surface and with a bolt hole extending through said part, a combined clamping and locking means for exerting a squeeze pressure on the jaw elements, said means including a screw element passed loosely through the bolt hole, having one end in threaded engagement with the nut and its opposite end forming a turning eye, said screw element provided between the turning eye and the adjacent jaw element with a pair of spaced apart shoulders, with the outer shoulder of greater diameter than the inner shoulder, the inner shoulder adapted when the screw element is rotated in one direction to engage the bearing surface and solidly lock the jaws relative to each

other particularly in the portions thereof which include the nut and the bearing surface, and a coiled spring encircling the screw element at all times under load having one end bearing on the outer shoulder and at its inner end bearing on said bearing surface, and the free end portions of the jaw elements outwardly beyond the nut and bearing surface having at least a slight degree of resiliency and coacting to provide a resilient wedge-like open throat for guiding the line into the seat therefor provided by the grooves whereby the device with its elements in unlocked position and under sole control of the spring can be forced on to the main line against the resistance of the spring.

2. A hot line connector provided with means for securing a tap line thereto, said connector including two clamping jaw elements formed of sheet metal with the elements hingedly connected, each element provided with a corrugation forming an inwardly facing groove for receiving one side of a main line clamped between the elements, one of the elements provided in offset relation to its corrugation with a nut fixedly secured thereto, a bolt passed loosely through the other element and in threaded engagement with the nut, said bolt on the side facing said other element provided with a bearing flange, a sleeve on the bolt and at the end adjacent said other element having an inturned flange overlapping the bearing flange on the bolt and at its outer end provided with an outturned flange, and a coiled spring at all times under load encircling the bolt and sleeve, bearing at one end on said other element and at its other end on the outturned flange of the sleeve, and said sleeve having a length greater than the length of the spring when compressed to a solid column.
